UNITED STATES PATENT OFFICE.

IRA A. WEAVER, OF SPRINGFIELD, ILLINOIS, ASSIGNOR, BY MESNE ASSIGNMENTS, TO MONTGOMERY WARD & CO., INCORPORATED, OF CHICAGO, ILLINOIS, A CORPORATION OF NEW YORK.

GANG-PLOW.

1,301,627.

Specification of Letters Patent. Patented Apr. 22, 1919.

Application filed June 15, 1914. Serial No. 845,094.

To all whom it may concern:

Be it known that I, IRA A. WEAVER, a citizen of the United States, residing at Springfield, in the county of Sangamon and 5 State of Illinois, have invented certain new and useful Improvements in Gang-Plows, of which the following is a specification.

My invention pertains to plows in general, but relates more particularly to gang 10 plows of the serial raising and lowering type.

One object of the invention is the production of an automatic lifting device for the plows, which will raise them and lower them 15 in sequence by power derived from one of the ground wheels, and which will be capable of permitting the plows to be raised manually, if required. Another object of the invention is the provision of means permitting 20 angular adjustment of the carrying wheel from which the power is derived for raising the plows, without interfering with the action of the lifting mechanism. A still further salient feature of the invention is the 25 provision of improved wheel-controlling mechanism in association with the draft bar.

Many other features of novelty and improvement will be apparent to those skilled in this art from the consideration of a preferred embodiment of the invention which is 30 set forth in the accompanying drawings forming a part of this specification, and described in detail below.

In these drawings,—

35 Figure 1 is a perspective view of a plow mechanism incorporating the features of the invention;

Fig. 2 is a plan view of the plow shown in Fig. 1;

40 Fig. 3 is a vertical section on line 3—3 of Fig. 2, the parts being viewed in the direction indicated by the arrows;

Fig. 4 is a fragmentary perspective view of a part of the plow, showing the same on 45 an enlarged scale;

Fig. 5 is a vertical section on line 5—5 of Fig. 6, through the axle of the carrying wheel from which power is derived for operating the lifting mechanism; and

50 Fig. 6 is a horizontal section just beneath the horizontal gear which such carrying wheel rotates.

Referring to the drawings, it will be observed that the machine frame, of general 55 triangular form, consists of a front bar 10

and a rear bar 11 connected together diagonally of the direction of travel of the appliance by a pair of spaced angle bars 12 and 13, to the horizontal flanges of which are fastened, in any approved manner, the 60 series of plow beams 14, 14, each carrying on its protruding rear end a revoluble disk-plow 15 and associated scraper 16. As is illustrated, the front and rear bars 10 and 11 extend beyond the companion angle-bars 65 12 and 13, and each, at the terminal of such protruding end, has fastened thereto a bracket 17 provided with a vertical bearing 18. The angle bar 13 has secured thereto a series of upwardly-extended brackets or supports 19 carrying at their upper ends a bar 20 disposed parallel to the angle bars 12 and 13, and acting not only to stiffen the frame, but also as a guard above the disks 15. The 70 left-hand end of the bar 20, as the parts are 75 viewed in Fig. 2, is bent rearwardly at 21 into register with the adjacent bracket 17, to which it is attached at 22.

The vertical bearing 18 of this bracket receives the upright cylindrical portion 23 of 80 the axle carrying the rear furrow-wheel 24. This axle 23 carries at its top end a bracket 25 with a bearing slidingly and revolvably receiving a screw 26 equipped with a turning handle 27, and internally engaging a threaded sleeve or rod 28 pivoted at 29 to one arm of a bell-crank 30 fulcrumed at 31 on the support or bracket 17; the other arm of the bell-crank having pivotal connection with a 85 forwardly-extended rod 32, described here- 90 inafter.

The axle of the wheel 24 has fixed thereto a bent bar 33 (see Fig. 2) adjustably pivoted to a link 34, the other end of which is pivoted at 35 to a rock-arm 36 oscillatingly 95 mounted on the angle bar 13 at 37. This rocker arm 36 has also connected thereto a rod 38 disposed beneath the plow beams and pivotally connected at its forward end to an arm 39 forming an extension of the draw-bar 40, which may be adjustably connected to the main frame in any one of a plurality of holes 41 in a plate 42 connected, as is illustrated in Fig. 2, to the ends of the two angle bars 12 and 13. Draw-bar 40, by 100 means of a connecting strap 43, is pivotally connected at 44 to an arm 45 of the axle of the front furrow-wheel 46.

As in the case of the rear furrow-wheel 24, the axle of this front wheel 46 has a ver- 110

tical cylindrical portion 47 rotatably received in the bearing 18 of the adjacent bracket 17, and at its upper end this axle has a cap 48 equipped with a bearing slid-
5 ingly and revolvably receiving a screw 49 having a turning handle 50, the screw being received within a threaded aperture of the connecting bar 51 pivoted at its lower end at 52 to one arm of a bell-crank 53 fulcrumed
10 at 54 on the bracket 17, the other arm of the bell-crank being pivotally connected to the end of a rod 55.

The other angle of the triangular frame is supplied with a pair of upper and lower
15 spaced bars 56 and 57, connecting together the two bars 10 and 11, the adjacent ends of which are spaced apart as is clearly shown in Figs. 5 and 6, the fastening means for the parts being conveniently the bolts 58.
20 The land wheel 59 is revolvably mounted on an axle 60, the inner portion of which is flattened, and extends between the two bars 56 and 57, to which it is fulcrumed on a pin 61 extended through apertures in the bars
25 and flattened part of the axle. The inner end of the axle is bifurcated at 62 and straddles a curved bar 63 fastened at its ends at 64 and 65 to the frame bars 10 and 11. Bar 63 has a plurality of apertures 66 permitting the axle, by means of apertures 67 in its bifurcated end and a pin 68, to be locked in any one of a number of angular positions; it being understood that during such angular adjustment, the axle and the wheel 59
30 35 turn about the fulcrum pin 61. In this way any desired lead of the land wheel may be easily obtained.

The hub of the wheel 59 carries a ratchet wheel 69, and loosely mounted on the axle
40 is a bevel pinion 70 having an arm 71, to which a pawl 72 is pivoted at 73, the pawl carrying a roller 74 adapted to coöperate with the teeth of the ratchet wheel so that the rotation of the ground wheel may be
45 transmitted through the ratchet and pawl to the pinion. The pawl is also supplied with a coöperating spring 72a.

The axle also has fixed thereto an arm 75 having a bearing 76 for the hinge pin 77 of
50 an operating lever 78 carrying a roller 79 adapted to coact with the tail of the pawl 72, the lever being normally pulled into the position illustrated in Fig 5 by a coiled contractile spring 80, whose outer end is fastened at 81 to a bar 82 secured to the axle, the other end of the spring being connected to a bent bar 83 fastened to the lever 78, so that the spring exerts a direct pull upon the lever.

60 The axle between the plates 56 and 63 is provided with a vertical bearing accommodating an upright shaft 84, on the top of which is mounted a horizontal bevel gear 85, the teeth of which are in mesh with those
65 of the bevel pinion 70. As is illustrated in

the various figures, gear 85 has upstanding therefrom a boss 86 equipped with a pin 87, on which the forward ends of the two lifting rods 82 and 83 are rotatably mounted. The under face of the gear 85 is supplied with two downwardly-extended pins 88 and 89, which of course revolve with the gear, and they are adapted to coöperate with the bent arm 90 (see Fig. 6) fulcrumed at 91 on the inward extension of the axle, and pivoted at 92 to one end of a link 93, the opposite end of which is pivoted to a boss or lug 94 on the inner face of the lever 78.

Operation: The manner in which this appliance performs its work is substantially as follows:

Assuming that the depth of cut of the plurality of disk plows has been determined by the adjustment of the screws 26 and 49, by their respective handles 27 and 50, and 85 that the plow is traveling forwardly in the usual manner, performing its customary plowing function, it will be obvious that, as the draw-bar 40 is shifted to one side or the other, the furrow wheels 46 and 24 will be 90 properly turned on their vertical pivots to assist in the guiding and steering of the apparatus. When the plow reaches the end of the field, and it is desired to lift the plurality of disks sequentially, so as to end all 95 furrows on a straight line transversely to the direction of travel of the machine, the operator pulls the handle 78 forwardly in opposition to the retracting influence of the coiled contractile spring 80. Of course the 100 land wheel 59 is consequently rotating, as well as the ratchet 69 carried on its hub, and as soon as the roller 79 on the arm 78 releases the pawl 72 by being withdrawn out of coöoperative relation with its tail, the 105 pawl, under the influence of its spring, 72a carries its roller 74 into one of the notches of the ratchet 69, thereby compelling the rotation of the arm 71 with the ratchet wheel, which rotation, of course, is transmitted to 110 the pinion 70 and horizontal bevel gear 85. Gear 85 has four times as many teeth as the pinion 70, and during the sequential raising of the disk plows, the gear 85 makes a half revolution. That is to say, the pinion 70, 115 the arm 71, ratchet 69, and wheel 59, make two complete revolutions in rotating the gear 85 a half revolution. It is necessary therefore to prevent the arm 78 and its roller 79 from engaging the tail of the pawl 72 120 and unclutching the latter from the ratchet 69 at the end of the first revolution of the ratchet. This is brought about by the pin 89 on the gear 85, which is so positioned on the gear that when the arm 71 and the pawl 72 have about completed the first revolution, it will have engaged the arm 90 and 125 swung it and the arm 78 outwardly so that the roller 79 cannot coöperate with the pawl. On the completion of the second revolution, 130

however, pin 89 will have moved away from arm 90, so that the arm 78, which, of course, has been previously released by the operator, has responded to the action of spring 80 and 5 brought the roller 79 in such position that, by engagement with the tail of the pawl, it has retracted the roller 74 from the ratchet, and broken the driving connection between the carrying wheel 59 and gear 85.

10 In order to secure the lifting of the plows one after the other so as to end the furrows evenly, obviously, the forward plow must be raised first and the others in sequence afterward. Since these plows are all mounted on 15 the same rigid frame, it is necessary to lift the forward end of the frame first, and the rear end afterward, after a proper time interval, or, rather, an interval dependent upon the travel of the machine. It will be 20 noticed that when the plows are down in operative position, as shown in Fig. 2, the angular relation of the lifting rods 55 and 32 with respect to the gear 85 and its axis is quite different; or, stated differently, the 25 rod 55 is beyond its dead center, and the rod 32 has not yet reached its dead center. The result is that, as soon as the gear 85 begins to turn in a clockwise direction as the parts are viewed in Fig. 2, the rod 55 immediately 30 begins to swing its bell-crank 53, and the corresponding bracket 17, forming a rigid portion of the forward end of the plow-supporting frame, begins at once to slide upwardly on the vertical axle or shaft 47, beginning the initial lifting movement of the 35 plows in proper order. The first part of this travel of the connection 87 causes no substantial movement of the bell-crank 30, or the rear end of the plow-frame; but as the pin 87 40 continues its rotation, it completes the lifting of the front end of the plow-frame, which remains substantially in that position because the remainder of the travel of the pin is on approximately the dead center of the 45 rod 55. On the other hand, however, when the pin 87 is approaching and passing through its dead-center position with respect to the rod 55, it is in its most efficient position for shifting the rod 32 and raising the rear 50 end of the plow-frame, whereby during the travel of the pin 87 through a half revolution the front end of the plow-frame is gradually raised and maintained lifted, and then the rear end of the frame is raised and maintained in such position, bringing about the proper and desirable sequential lifting of the 55 plows due to their diagonal disposition across the plow-frame.

Obviously, this elevation of the plows is 60 brought about by a mechanism extremely simple in structure and entirely automatic in its operation after the control lever has once been manipulated to throw the parts into clutched relation, the power for the lifting of the plows being secured directly from

one of the carrying wheels, in this instance the land wheel. It is furthermore to be observed that this lifting of the plows in sequence, although brought about by the rotation of a single pin, is secured by reason 70 of the relation of the lifting rods to such pin, so that the speeds of travel of the rods will be so different as to occasion a prompt lifting of the front end of the plow-frame and a delayed elevation of the rear end, which of 75 course causes the desired serial lift.

When it is desired to begin plowing and to have the ends of all of the furrows even crosswise of the direction of travel of the machine, the operator again manipulates the 80 handle 78, either directly or by means of a pulling cord, and then the gear 85 will make its other half revolution and stop; the carrying wheel 59, ratchet 69, pinion 70, and associated parts, making two complete revolutions, as in the previous instance, and automatically stopping. When the gear 85 starts, the pin 87 has passed the dead center as far as the rod 55 is concerned, but has not yet reached the dead center as far as the 90 rod 32 is concerned, so that the rod 55 will at once lower the front end of the plow-frame, and, after once being lowered, will maintain it substantially in that position, because during the remainder of the travel of 95 the pin 87 it is approaching and passing by dead center. On the other hand, when this pin 87 begins its rotation, there is substantially no movement of the rear end of the plow-frame because the pin is approaching 100 and passing dead center with respect to the rod 32, and then travels in a path favorable for a substantial movement of the rod 32, which it occasions, resulting in the delayed descent of the rear portion of the plow-frame. In this way the plows are lowered sequentially, the operation being substantially the reverse of that which takes place 105 during the lifting. During the plow-lowering operation the pin 88 on the gear prevents the parts unclutching at the end of the first revolution of wheel 59.

It should be observed that the angular position of the land wheel 59 may be varied within wide limits without interfering with 115 or modifying the action of the automatic plow-lifting mechanism, this being rendered possible by reason of the fact that the various parts of this mechanism are all carried on or supported by and movable with the 120 axle as it is shifted to different positions of adjustment.

Attention is also summoned to the fact that the independent hand-lifting mechanism for the plows and their frame is 125 directly connected to, and in a certain sense forms a part of, the automatic lifting mechanism shown and described. This manual lifting appliance may be employed for adjusting the depth of cut, and may also be 130

used if for any reason the automatic lifting mechanism is put out of commission by accident.

A further feature of this appliance to be noted is that the clutch controlling mechanism, inserted between the carrying wheel and the lifting mechanism which it operates, permits more than one revolution of the drive wheel to effect the lifting of the plows, 10 which of course permits a more effective and advantageous use of the power employed.

It should be observed, that, since the screws 26 and 49 support the frame from the upper ends of the vertical axle portions 23 and 47 15 and have sliding association with their bearings in the caps 25 and 48, the plow-frame and plows are free to rise without lifting or interfering with the action of the carrying-wheels, which construction permits the plows 20 and frame to ascend in riding over an obstruction without swinging or swerving the wheels from their course as would be likely to occur if the wheels were lifted by the plows traveling over the obstacle. A structure 25 of this character remains substantially true to its course even though the action of the plows is interfered with by obstructions over which they pass.

I claim:

30 1. In a construction of the character described, the combination of a plow-support, a plurality of plows carried thereby, a pair of lifting means connected to said support at different points, a power-driven rotary member, and a pair of connections between said pair of lifting means and said rotary member at one side of the axis thereof and disposed at an angle to each other and at different angles to said rotary member in substantially the plane of rotation thereof, whereby when one connection operates relatively rapidly on its lifting means the other operates relatively slowly on its lifting means, and vice versa, substantially as described.

2. In a plow, the combination of a frame, carrying wheels and their axles therefor, a plow-lifting mechanism adapted to be operated by one of said wheels, and means permitting angular adjustment of the axle of said wheel to change the lead independently of and without interfering with the action of said lifting mechanism, substantially as described.

55 3. In a plow, the combination of a frame, carrying wheels and their axles therefor, one of said axles being bodily adjustable angularly to change the lead, a plow-lifting mechanism adapted to be operated by the wheel 60 of said adjustable axle, and a clutch mechanism and clutch-controlling mechanism mounted on said axle and adapted to clutch the carrying wheel of said axle to the plow-lifting mechanism and unclutch it therefrom, 65 substantially as described.

4. In a plow, the combination of a frame, carrying wheels and their axles therefor, one of said axles being bodily adjustable angularly to change the lead, a plow-lifting mechanism adapted to be operated by the wheel 70 of said adjustable axle, a clutch mechanism, clutch controlling mechanism and co-operating gears mounted on said axle, and means connecting one of said gears to the plow-lifting mechanism, substantially as described. 75

5. In a plow, the combination of a frame, carrying wheels and their axles therefor, one of said axles being bodily adjustable angularly in a substantially horizontal plane to change the lead, a plow-lifting mechanism 80 adapted to be operated by the wheel of said adjustable axle independently of such adjustment, a clutch mechanism mounted on said adjustable axle, a clutch-controlling mechanism mounted on said adjustable axle, 85 a pinion on said axle, a horizontal gear revolvably mounted on said axle and in mesh with the pinion, and means connecting said horizontal gear to the plow-lifting mechanism, substantially as described. 90

6. In a plow, the combination of a frame, a pair of carrying wheels mounted on axles with vertical portions, a third carrying wheel mounted on a horizontal axle bodily angularly adjustable on said frame to 95 change the lead, said frame being vertically adjustable on said vertical axle portions, a plow-lifting mechanism connected to the frame near one of said vertical portions, a second plow-lifting mechanism connected to 100 the frame near the other vertical axle portion, a horizontal gear revolvably carried by the angularly adjustable horizontal axle, means connecting said horizontal gear with the carrying wheel of the adjustable axle 105 whereby the rotation of the carrying wheel may be transmitted to the gear independently of the adjustment of said axle, and connecting rods connecting said gear with said pair of lifting mechanisms, substantially 110 as described.

7. In a construction of the character described, the combination of carrying wheels, a frame, a plurality of plows arranged in a series diagonally of their direction of travel, 115 and a lifting and lowering mechanism for said plows including rigid link connections and operated by power derived from one of the carrying wheels and adapted to raise and lower the plows in sequence, said mechanism 120 performing its lifting function during a plurality of revolutions of said carrying wheel and performing its lowering function during a plurality of revolutions of said carrying wheel, substantially as described. 125

8. In a construction of the character described, the combination of carrying wheels, a frame, a plurality of plows arranged in a series diagonally of the direction of their travel, a lifting and lowering mechanism for 130

- said plows including rigid link connections and operated by power derived from one of the carrying wheels and adapted to raise and lower the plows in sequence, and performing its plow lifting and lowering functions each during a plurality of revolutions of said power-transmitting carrying wheel, a clutch between said carrying wheel and lifting mechanism, and means to render said clutch inoperative only after the carrying wheel has turned its plurality of revolutions, substantially as described.
9. In a construction of the character described, the combination of carrying wheels, a plow-support, a plurality of plows mounted on said support and arranged in a series diagonally of the direction of their travel, and a plow-lifting mechanism including rigid link connections and adapted to raise the plows in sequence and operated by power derived from one of the carrying wheels, said lifting mechanism including a rotary member connected to lifting devices at opposite ends of the plow-support, said rotary member making a half revolution to perform the plow-lifting function while the power-transmitting carrying wheel makes a plurality of revolutions, substantially as described.
10. In a plow-construction of the character described, the combination of three carrying-wheels, a pair of axles for two of said wheels having vertical portions, a frame carried by said wheels and vertically slidable on said axle portions, plows mounted on said frame, axle-caps on the tops of said axle portions, manually-operable means supporting said frame from said caps and adapted to adjust the depth of cut and raise the plows by lifting the frame, means to lift the plows and frame operated by the third wheel and including said manually-operable means, the latter being freely slidable through said axle-caps whereby the plows and frame may rise as the plows ride over an obstruction without lifting the pair of carrying wheels, substantially as described.
11. In a plow-construction of the character described, the combination of carrying-wheels, a frame mounted on said wheels, a plurality of plows carried by said frame, means operated by one of the carrying wheels to raise and lower said plows in sequence, an axle for said wheel horizontally angularly adjustable on said frame to vary the lead of the wheel independently of the raising and lowering mechanism, and a clutch on said axle adapted to connect said wheel to and disconnect it from said raising and lowering mechanism, said wheel making a plurality of revolutions during each plow raising and lowering operation, substantially as described.
12. In a plow-construction of the character described, the combination of carrying-wheels, a frame mounted on said wheels, a plurality of plows carried by said frame and arranged in a series diagonally of the direction of travel of the machine, means to raise and lower said plows operated by one of the carrying-wheels, an axle for said wheel horizontally angularly adjustable on said frame independently of the raising and lowering mechanism, a clutch on said axle adapted to connect said wheel to and disconnect it from said raising and lowering mechanism, and means mounted on said axle controlling the operation of said clutch, said wheel making a plurality of revolutions during each plow raising and lowering operation, substantially as described.

In witness whereof, I have hereunto signed my name, this 8th day of June, 1914.

IRA A. WEAVER.
